UNITED STATES PATENT OFFICE.

RUDOLPH HOYER, OF NEW YORK, N. Y.

DESIGN FOR HARNESS-TRIMMINGS.

Specification forming part of Design No. **7,071**, dated December 23, 1873; application filed November 1, 1873.
[Term of Patent 7 years.]

To all whom it may concern:

Be it known that I, RUDOLPH HOYER, of the city, county, and State of New York, have invented a new and original Design for Harness-Trimming, of which the following is a specification:

The design is a checkered ground, and is produced of leather strips of suitable lengths, and of varying colors, which are braided together in such a manner that a checkered band is obtained.

This trimming, B, is applied to the harness straps or pads by lining C, of suitable color, in the usual raised manner, being, however, by preference, so arranged that a symmetrical position of the checkers is obtained between the lining C. The checkers of the trimming

may be placed parallel to, or diagonal to, the lining.

I am aware that such trimming has been used with lateral strips of different colors, and with zigzag strips; but the distinctive feature of my design is found in the checkered trimming, which is applied as border or face ornament to the harness parts.

I claim as my invention—

The design for harness-trimmings, consisting of a checkered band braided of different colors, and a lining arranged therewith, substantially in the manner described and shown.

RUDOLPH HOYER.
